CLAIM

The ornamental design for a syringe, as shown and described.

DESCRIPTION

FIG. 1 is a perspective view of a first embodiment of a syringe showing my new design;

FIG. 2 is a front view of the first embodiment of the syringe;
FIG. 3 is a right side view of the first embodiment of the syringe;

FIG. 4 is a rear view of the first embodiment of the syringe;
FIG. 5 is a left side view of the first embodiment of the syringe;

FIG. 6 is a top view of the first embodiment of the syringe;
FIG. 7 is a bottom view of the first embodiment of the syringe;

FIG. 8 is a perspective view of a second embodiment of the syringe;
FIG. 9 is a front view of the second embodiment of the syringe;

FIG. 10 is a right side view of the second embodiment of the syringe;
FIG. 11 is a rear view of the second embodiment of the syringe;

FIG. 12 is a left side view of the second embodiment of the syringe;
FIG. 13 is a top view of the second embodiment of the syringe;

FIG. 14 is a bottom view of the second embodiment of the syringe;
FIG. 15 is a perspective view of a third embodiment of the syringe;

FIG. 16 is a front view of the third embodiment of the syringe;
FIG. 17 is a right side view of the third embodiment of the syringe;

FIG. 18 is a rear view of the third embodiment of the syringe;
FIG. 19 is a left side view of the third embodiment of the syringe;

FIG. 20 is a top view of the third embodiment of the syringe;
and,

FIG. 21 is a bottom view of the third embodiment of the syringe.
(Continued)

The lined pattern on the plunger portion represents the color purple. No specific shade of purple is claimed.
